COMBINATION BOTTLE UNCAPPER,
RECAPPER, AND ICE-BREAKER

Miles O. Polson, Flagstaff, Ariz.

Application November 14, 1947, Serial No. 786,011

1 Claim. (Cl. 226—84)

1

This invention relates to tools for removing and replacing bottle caps, and more particularly to a combination tool for uncapping and recapping bottles and for crushing ice.

A main object of the invention is to provide a novel and improved combination tool for uncapping and replacing caps on bottles, and serving also as an ice crushing implement, said tool being very simple in construction, easy to operate and efficient in performance.

A further object of the invention is to provide an improved bottle cap removing device which is also employed to recap bottles by impact, the impact being derived by means also serving at times for crushing ice, said device being inexpensive to manufacture, rugged in construction, and reliable in operation.

Further objects and advantages of the invention will become apparent from the following description and claims, and from the accompanying drawings, wherein:

Figure 1 is an elevational view of a combination tool constructed in accordance with the present invention.

Figure 2 is a vertical cross-sectional view taken on line 2—2 of Figure 1.

Figure 3 is a horizontal cross-sectional view taken on line 3—3 of Figure 2.

Figure 4 is a bottom end view of the tool, taken on line 4—4 of Figure 2.

Referring to the drawings, 11 generally designates the tool. The tool comprises an elongated rigid rod 12 which is threaded at its top and bottom ends. Secured to the bottom end of rod 12 by means of nuts 13 and 14 is a rigid cap member 15 having a cylindrical skirt portion 16. Encircling rod 12 and welded or otherwise rigidly secured thereto a short distance above the nut 13 is a washer 17 serving as a stop or anvil. Overlying the washer 17 and encircling the rod 12 is a cushion washer 18 of rubber or the like.

Threaded onto the top end of rod 12 is a member 19 serving as a bottle cap remover, said member being locked rigidly to the rod by a nut 20 bearing upwardly on a split spring lock washer 21 interposed between nut 20 and hook member 19. The member 19 comprises a relatively long upstanding arm 22 and a relatively short upstanding arm 23 spaced from arm 22 and formed with a concave bottle neck engaging edge 24. The member 19 is employed to uncap a bottle by placing the long arm 22 over the bottle cap with the short arm 23 engaged under the edge of the skirt of the cap and then swinging rod 12 upwardly, the bottle being meanwhile held firmly.

2

Arm 22 fulcrums on one top edge of the cap, whereby the opposite side of the cap is lifted off the mouth of the bottle by the short arm 23.

Designated at 25 is a weight member, of heavy metal or the like, which is slidable on rod 12 between nut 20 and resilient washer 18. In recapping a bottle, the cap is placed on the bottle mouth and cap member 15 is placed over the cap with rod 12 in vertical position. Weight 25 is raised to a substantial height on rod 12 and allowed to drop onto the resilient washer 18. The impact of weight 25 is transmitted to cap member 15, which is thereby forced downwardly over the corrugated skirt of the bottle cap, pressing the skirt corrugations inwardly over the bead on the bottle mouth. This firmly locks the cap on the bottle mouth in sealing relation thereon, whereby the gaseous or liquid contents of the bottle is retained therein until the bottle is again opened.

The upper portion of rod 12 is formed with a transverse bore 25' and is flattened at opposite sides thereof sub-adjacent said bore, as shown at 26, 26. Secured in said bore is an inverted U-shaped spring wire member 27 having side arms extending downwardly along said flattened surfaces 26, 26 and protruding slightly with respect to the cylindrical surface of rod 12. The upper portion of member 27 is surrounded by and locked to rod 12 by nut 20 in the manner indicated in Figure 2.

The side arms of member 27 may be frictionally engaged with the bore of weight member 25 by raising said weight member into abutment with the nut 20. This serves to frictionally secure the weight member in elevated position on the rod 12. By employing the lower portion of rod 12 as a handle, the weight member 25 may then be utilized as a hammer for crushing ice for use in cold drinks and the like. The weight member 25 may be readily released by manually pulling it downwardly out of frictional engagement with the resilient side arms of the U-shaped spring member 27.

The cap member 15 is formed to closely fit the top portion of a bottle cap so that when it is driven downwardly by the impact of the descending weight member 25 it will provide the necessary inward crimping force on the corrugated skirt of the bottle cap. The resilient washer 18 cushions the impact of weight member 25 to prevent shattering the bottle by the shock resulting from the sudden termination of the descent of the weight member.

While a specific embodiment of a combination

bottle uncapper, bottle recapper and ice crushing tool has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

In combination, a rod, a weight mounted on 10 said rod for movement therealong, combined stop and retaining means on said rod and spaced from one end of the rod and with which said weight is adapted to be engaged when moved along the rod in a direction away from said one end of the rod, said weight having a bore slidably engaging said rod, said means comprising a member fixed on said rod with which the weight is adapted to engage when moved in the said direction, a resilient element on said rod including spring arms 15

extending along opposite sides of the rod and arranged to be frictionally engaged by the bore of the weight whereby the weight is releasably held in engagement with said member, an abutment adjacent and secured to the opposite end of said rod having a surface to receive impact from said weight, and a tool operated by said impact. 20
